UNITED STATES PATENT OFFICE.

HUGO C. KNUDSEN, OF BROOKLYN, NEW YORK.

EXPOSING-TABLE.

1,151,477.

Specification of Letters Patent. Patented Aug. 24, 1915.

Application filed September 25, 1911. Serial No. 651,079.

To all whom it may concern:

Be it known that I, HUGO C. KNUDSEN, a subject of the King of Denmark, residing in the borough of Brooklyn, county of Kings, 5 and State of New York, have invented certain new and useful Improvements in Exposing-Tables, of which the following is a specification.

The invention relates to exposing tables 10 for use in making prints upon a light sensitive surface by the action of light wherein contact is made or perfected by atmospheric pressure, and more especially to making an impression by means of a light transmitting 15 flexible negative or other design bearing member on a metal or other plate or sheet having a light sensitive surface.

Objects of the invention are to provide 20 for perfect contact by atmospheric pressure between all parts of a negative or design carrying element and a plate or sheet having a sensitive surface upon which the design from such negative or element is to be impressed by the action of light; more 25 especially to provide perfect contact by atmospheric pressure between a relatively rigid metal plate or sheet, having a more or less irregular surface and a flexible negative or design sheet during the impression 30 of the picture or design upon the sensitized surface of such plate or sheet; to provide against formation of wrinkles or air pockets between the flexible negative or design sheet and the metal plate; to provide for the easy 35 removal of such wrinkles or air pockets in case there is a tendency toward their formation at first; to provide for a uniform action of the vacuum throughout; and to provide a generally superior and useful novel 40 construction of exposing table. These and other objects of invention will in part be obvious and will in part more fully appear herein.

The invention consists in the novel constructions, arrangements, manufactures, 45 parts, combinations and improvements herein shown and described.

The accompanying drawings, referred to herein, and forming a part of this specification, 50 illustrate one embodiment of the invention, the same serving in connection with the description herein to explain the principles of the invention.

Of the drawings: Figure 1 is a front elevation of an exposing table constructed in 55 accordance with the principles of the in-

vention, the clamping frame being shown in elevated position (as in Fig. 3) for the sake of clearness; Fig. 2 is a section view, showing particularly the construction of the 60 supporting table, and the connection to the vacuum pump; Fig. 3 is an elevation looking at Fig. 1 from the right; Fig. 4 is a fragmentary sectional view, on an enlarged scale, on the line A—B of Fig. 3, but showing 65 the clamping frame down and with a printing plate, negative, and the air conveying (or pervious) and non-air conveying (or impervious) coverings in position, that is, showing these elements by way of example as used in making a printing plate; Fig. 5 is a similar view to Fig. 4 but showing 70 a different supporting means for the plate, comprising a perforate metal sheet or layer; and Fig. 6 is a similar view showing 75 the perforate metal sheet or layer stretched over a layer of felt.

Referring by way of example to the illustrated embodiment, a support of suitable form for the exposing table is provided, and 80 as shown comprises uprights 1 and 2 supported on base pieces 3 and 4, the exposing table being journaled upon said uprights 1 and 2. For convenience the base pieces 3 and 4 may be supported on casters 5. Angle 85 braces 6 and 7 are provided between the upright 1 and the base piece 3, and similar braces are provided between the upright 2 and the base piece 4, the angular brace 8 appearing in Fig. 1 of the drawings. Cross 90 frame pieces or braces 9 and 10 are used to connect the uprights 1 and 2. Journaled upon the uprights 1 and 2, by means of pin 95 tles or trunnions 15 and 16, is the exposing table, comprising a rectangular frame consisting of the members 17, 18, 19 and 20 suitably joined together. The supporting portion of the exposing table may be constructed of any suitable rigid material, and is shown comprising a board or series of 100 boards 21 supported on shoulders 22 formed in said frame members of the table. The board or boards 21 are further shown covered by a metal plate 23, which plate also extends outwardly over the surface of the 105 frame members 17, 18, 19 and 20. It will be understood that these details of construction are not essential, the purpose being to provide as nearly as possible a level, firm and unchanging supporting or table surface. 110 Carried upon the upper surfaces of said frame members is a resilient sealing device,

preferably strips of rubber 24. These extend all the way around on the top of the frame and form with the clamping frame, or sealing devices on the clamping frame, 5 when in its closed position, an air tight joint.

The clamping frame is preferably hinged to the frame of the exposing table proper. As embodied it comprises four rectangular frame members 30, 31, 32, and 33 connected 10 to the exposing table along the member 32 by hinges 34. A resilient sealing member on the clamping frame, to coöperate with the sealing member 24 on the exposing table frame, is provided, and is shown as a strip 15 36 of rubber carried on the under surface of the members of the clamping frame, so that when the clamping frame is down and clamped tight, these two resilient members will be pressed together entirely 20 around the exposing table (as fragmentarily shown in Fig. 4) for the purpose of securing more certainly a firm contact and air-tight seal all around. The contacting surfaces of either one or both of the opposed 25 sealing members may be more or less rounded, and the surface of the sealing member 36 is so shown in Fig. 4.

Clamping devices of suitable or approved form for tightly clamping together the table frame and the clamping frame are provided and as shown herein comprise threaded rods 37, pivoted to the table frame, and carrying nuts 38 adapted to fit into brackets 39 on the clamping frame.

35 Suitable means for holding the clamping frame in an elevated position are provided and are shown as comprising one or more curved and notched bars 40 pivoted at 41 on the clamping frame each working in an orifice in a member 42 fixed on the table frame, and the notches on the bar adapted to engage with the upper edge of the member 42 to support the clamping frame in its elevated position. Means of suitable or convenient form are also provided for inclining 45 the exposing table as desired, and for preventing movement thereof by reason of changes in the center of gravity, due to the elevation of the clamping frame or other causes. The illustrated form of such means comprises a curved bar 43 having both ends thereof fixed to the side frame of the exposing table, and having a clamping screw 44 carried by one of the uprights 1 or 2 to hold 50 it in position.

55 For the purpose of bringing the negative or design sheet and the sensitized surface of the plate into absolute contact in all parts thereof despite the inevitable unevennesses 60 and irregularities in the surface of the plate, means are provided whereby the negative and plate are pressed together uniformly through the entire area thereof by atmospheric pressure exerted upon a flexible impervious sheet (that is, non-air transmitt-

ting) which is clamped between the frames of the exposing table and clamping frame and sealed by the sealing members, the sensitized plate being supported upon the table, and the negative in contact with the sensitized surface of the plate beneath said 70 impervious flexible sheet (Fig. 4).

Means are provided by the invention for permitting the transverse travel or seepage of the air between the negative and the impervious flexible light transmitting element which acts to press the negative against the plate. As embodied this consists of a layer of light-transmitting, porous (that is, air conducting) material interposed between 80 said light conducting impervious element and the negative. Thus, the impervious element may press closely against all parts of the negative, the pressure being transmitted by the intervening pervious element, and at 85 the same time as the vacuum increases the residual or gradually rarefying air may pass out or travel parallel to the surface of the plate and negative, thus insuring perfect contact all over the surface of the plate 90 and despite the inevitable small irregularities in the surface of the plate. The impervious flexible sheet cannot in the early stages of the rarefying or vacuum creating process be pressed tightly against the edges 95 of the negative and plate, and thus tend to seal the area above the plate and prevent further rarefaction there. Also, when the suction device is acting a continuing uniform condition of pressure is maintained on 100 all the parts of the surface of the plate. Thus a uniformly sharp and perfect impression is made all over the plate by the action of the light through the negative or design carrying sheet.

105 As a part of the supporting means for the plate there is included beneath the plate a supporting member of the requisite firmness, but being also pervious to air, so that it may form a firm support for the plate and at the same time permit the air to pass out when the air exhausting means is beneath the plate as in the embodied form. In Fig. 5 this support is shown as a foraminous metal sheet or layer 56 which may be of interwoven wire 110 or other suitable construction, sufficiently fine to afford a solid support for the plate 51, while the air will pass easily therethrough. In Fig. 4 a layer of felt 50 is shown as such air transmitting support. This layer will be of hard and firm texture but will also be pervious to the air. In Fig. 6 a layer of wire netting or stamped metal 115 56 is shown stretched over a layer 50 of felt for supporting the plate 51. On this supporting means (Figs. 4 and 5) is shown a metal plate 51 having its upper surface light sensitive, and on this a flexible negative 52. The layer 53 of pervious material is shown above the negative and over this layer of 120 130

impervious material 54, which is tightly clamped all around between the sealing members 24 and 36.

- The vacuum creating means comprises a 5 pump or other suitable device (not shown) connected by a conduit 55 through the table, thus communicating with the inclosed space between the table and the impervious member 54 and the sealing members 24 and 36.
- 10 I prefer also that the layer of felt or like material 50 be imperforate over the opening of the conduit 55, for by reason of the porosity of the layer 50 the air seeps or travels therethrough, and the vacuum is created just 15 the same, while the layer 50 prevents the formation of a slight cup or depression in the plate 51 just over the opening of the conduit 55, to thus destroy the contact at that point. It will be understood, there- 20 fore, that an air tight area or space is formed between the impervious flexible sheet 54, the sealing members 24 and 36 and the plate 23, and that while firm pressure is exerted by the atmosphere to hold the printing plate 25 51 to the table and the design carrying sheet 52 to the printing plate, yet the air can travel along the surface of the negative and beneath the printing plate and thus secure and hold a strong and uniform atmospheric 30 pressure through the entire area partly formed by the negative and printing plate.

The manner of operation of the device will be clearly understood from the foregoing, and it will be seen that the objects of 35 invention are realized by means of the embodiment described and illustrated.

What I do claim as my invention and desire to secure by Letters Patent, is:

1. Frames having opposed sealing elements, a support carried by one frame, a flexible light transmitting sheet impervious to air adapted to be held between the sealing elements, and means through which air may be exhausted from between the sheet 45 and support.
2. Frames having opposed sealing elements, a support carried by one frame, a flexible light transmitting sheet impervious to air adapted to be held between the seal-

ing elements, means located between said sheet and the support and adapted to permit transverse travel of the air therebetween, and means through which air may be exhausted from between the sheet and support.

3. Frames having opposed sealing ele- 55 ments, a support carried by one frame, a flexible light transmitting sheet impervious to air adapted to be held between the sealing elements, a sheet pervious to air adapt- 60 ed to be positioned between the said support and impervious sheet and means through which air may be exhausted from between the impervious sheet and support.

4. An exposing table including in combi- 65 nation a support upon which is adapted to rest a plate having a light sensitive surface, said plate adapted to carry a flexible light transmitting design carrying sheet, a flexible light transmitting sheet impervious to air located above the support, means for seal- 70 the edges of said impervious sheet to render the space between said sheet and said support air tight, a sheet pervious to air between the impervious flexible sheet and sup- 75 port, and means through which the air may be exhausted from said air tight space.

5. An exposing table including in combi- 80 nation a support upon which is adapted to rest a plate having a light sensitive surface, said plate adapted to carry a flexible light transmitting design carrying sheet, a flexible light transmitting sheet impervious to air located above the support, means for seal- 85 ing the edges of said impervious sheet to render the space between the said sheet and said support air tight, means entering through said support and through which the air may be exhausted from said air tight space, and means permitting the air to travel beneath said plate on the support to said 90 exhausting means.

In testimony whereof, I have signed my name to this specification, in the presence of two subscribing witnesses.

HUGO C. KNUDSEN.
